SYLVANIA.

INSULATOR-SUPPORT.

1,197,659.

Specification of Letters Patent. Patented Sept. 12, 1916.

Application filed February 5, 1916. Serial No. 76,301.

To all whom it may concern:

Be it known that I, CHARLES L. PEIRCE, Jr., a citizen of the United States, and a resident of Pittsburgh, in the county of Allegheny and State of Pennsylvania, have invented certain new and useful Improvements in Insulator-Supports, of which the following is a specification.

My invention relates to insulator supports which are stronger and more practical and efficient than insulator supports heretofore used.

My invention relates particularly to insulator supports comprising a bracket member and thimble structure secured thereto.

Heretofore bracket members have been formed up from metal stock shapes such as channel bar, and thimble structures applied to the ends thereof. The parts of the thimble structures which receive the insulators must be of circular cross-section but when such structures are applied to bracket members of stock material the base parts of the thimbles must be bent to fit the contour and angles of the bar and this of course weakens the support at the very section where it should be strongest. Where the thimble structures are sectional in order to yield radially when an insulator is applied the sections are apt to bend permanently if the cylindrical form or circular cross-section below the thimble structure threads has been destroyed by bending the insulator structure to fit the bracket member end. In other words, circular cross-section throughout the thimble structure will give the greatest strength and if such circular cross-section is in any wise destroyed the thimble structure and the entire support will be correspondingly weakened.

The bracket member itself, when bent up from stock material has its disadvantages. In the first place, the stock must be taken as it is and the desired strength at one section cannot be obtained without too much stock at some other section, and consequently over-weight and waste. In the second place, when the support is formed up of stock material, for example channel bar, and the thimble structure is bent to fit, there will be sharp edges and corners on which wires could chafe or get caught.

The object of my invention is to overcome the disadvantages of the above referred to structures and to produce an insulator support comprising a bracket member built up entirely from flat sheet metal accurately dimensioned and bent to such form as to give the desired strength at each section without over-weight and to provide a cylindrical or conical seat for a thimble structure also formed up from flat sheet metal and of circular section throughout. Such construction will insure the greatest strength where it is most needed, namely, at the base of the thimble structure threads and adjacent the end of the bracket member to which the thimble structure is secured, and such circular cross-section throughout the insulator structure will also prevent permanent bending of the insulator structure sections.

On the accompanying drawing I show an insulator support which embodies the various features of my invention.

On this drawing Figure 1 is a side elevational view of the support, Fig. 2 is a front elevational view, Fig. 3 is a sectional view on plane 3—3, Fig. 2, Fig. 4 is a sectional view on plane 4—4, Fig. 1, and Fig. 5 is a perspective view showing one manner of applying the insulator support to a supporting base.

The insulator support shown comprises a bracket member B and a thimble structure T. The bracket member shown is of U-shape and is bent up entire from a single piece of flat sheet metal stock to be of arched cross-section. The bracket member throughout its body part 10 is open, that is, the limbs 11 and 12 are separated at their ends and may be parallel as shown or at angles with each other. At the outer end of the body part the limbs 11 and 12 are brought together to form a seat e of circular cross-section for receiving the thimble structure T. The thimble structure shown is of circular cross-section throughout and is sectional, two semi-cylindrical sections 13 and 14 being shown. These sections intimately fit at their bases against the cylindrical sides of the end e and as shown are secured by a rivet 15 extending therethrough and through the end e. The section may be ap-

plied in any desired arrangement to the bracket member end. As shown, the section 13 covers the jointure *j* of the bend in limbs 11 and 12 at the end *e* and the rivet passes 5 through this jointure. The upper parts of the sections 13 and 14 are somewhat conical and are threaded to receive an insulator. In order that the sections may yield radially during application of the insulator they are 10 normally separated at their edges by gaps 16 and 17. The thimble structure sections are formed integral from flat sheet metal stock and the threads are stamped in such manner that they will register when the 15 finished sections are applied to the bracket member.

With the above arrangement involving the circular seat for the thimble structure which is of circular cross-section throughout, the support retains maximum strength where such strength is the most necessary, namely, just below the threads. Furthermore, the circular cross-sectional structure throughout will retain the full elasticity of 20 the thimble sections and will prevent permanent bending or give thereof when an insulator is applied and the sections are brought together, and after application of the insulator the sections will, by their spring and 25 elasticity, securely clamp the insulator in place. Instead of constructing the thimble structure of only two sections as shown, it is evident that they could be sub-divided into a greater number of sections which 30 would be separated at their edges to yield radially to receive the insulator and to then clamp the insulator to the support.

Any suitable arrangement may be provided for securing the support to a wall, 40 pole or other supporting structure. As shown in Figs. 1 and 2, ears 18 and 19 are formed integral at the inner end of the bracket member and have bolt holes 20 and 21 respectively. Instead of being secured 45 individually to supports, a number of brackets could be mounted on a common support. In Fig. 5 such arrangement is shown. The open arched backs of the bracket members B saddle over an arched frame 22 and straps 50 23 arch over each bracket and are secured thereto and to the frame by riveting 24, the strap having the wings or flanges 25 and 26 provided with bolt holes 27 by means of which the frame 22 with the various brackets thereon may be secured to a wall or pole.

In the insulator support described there is no waste of metal or over-weight. The blanks for the bracket member and thimble structure are accurately dimensioned before 60 forming in accordance with the desired strength and are then bent into such form as will result in the greatest strength. The arch section bracket member is open outwardly leaving the rounded arch surface on

the inner side so that it will be impossible 65 for wires to chafe or catch. Likewise, the thimble receiving end being circular and free of corners, there will be no chance for wires to chafe or get caught at such end or on the thimble structure. 70

I do not of course desire to be limited to the precise construction and arrangement shown as modifications may be possible which would still come within the scope of 75 the invention.

I claim as follows:

1. An insulator support consisting of a bracket member formed up entire from a single piece of flat sheet metal and having an end of circular cross-section, and a thimble structure of circular cross-section throughout and comprising threaded sections each formed up entire from a single piece of sheet metal, said sections being secured to the circular end of the bracket 80 member. 85

2. An insulator support consisting of a bracket member and a thimble structure, said bracket member being formed up from a single piece of flat sheet metal and having an end of circular cross-section, said thimble structure being of circular cross-section throughout and composed of sections secured at their bases to the circular end of the bracket member, said sections being 90 threaded to receive an insulator and being separated a distance at their longitudinal edges to yield radially when an insulator is applied. 95

3. An insulator support consisting of a bracket member and a thimble structure, said bracket member being formed up entire from a single piece of flat sheet metal stock and comprising an open body of arch cross-section and a closed end of circular cross-section, said thimble structure being of circular cross-section throughout and composed of a number of sections of arcuate cross-section intimately engaging and secured at 100 their bases to the closed end of said bracket 105 member, said sections being threaded to receive an insulator and being separated sufficiently to yield radially when an insulator is applied. 110

4. An insulator comprising a bracket member and a thimble structure, said bracket member being bent up from a flat piece of sheet metal and having an end of circular cross-section, said thimble structure being of circular cross-section throughout 115 and being composed of a number of sections engaging at their bases with the circular end of the bracket member and riveted thereto, said sections being threaded for the reception of insulators. 120

5. An insulator supporting structure comprising a body part bent up from a flat piece of comparatively heavy sheet metal 125

with the sides at one end curved and brought together to form a seat of circular cross-section, and a plurality of sections of thinner sheet metal each of arcuate cross-
5 section throughout and threaded, said sections being applied intimately against the side of the body end and secured thereto to

thereby form an insulator receiving thimble of circular cross-section throughout.

In witness whereof I hereunto subscribe 10 my name this 1st day of February, A. D., 1916.

CHARLES L. PEIRCE, JR.
